UNITED STATES PATENT OFFICE.

GUSTAV R. KELM, OF NEW YORK, N. Y., ASSIGNOR TO W. M. LEVETT AND WALKER M. LEVETT CO., OF NEW YORK, N. Y., A CORPORATION OF NEW YORK.

METAL MOLD FOR PISTON CASTINGS.

Application filed August 24, 1922. Serial No. 504,001.

To all whom it may concern:

Be it known that I, GUSTAV R. KELM, a citizen of the Polish Republic, residing in the city, county, and State of New York, have invented new and useful Improvements in Metal Molds for Piston Castings, of which the following is a specification, reference being had to the accompanying drawings, in which—

Fig. 1 is a section of a piston mold embodying my invention; Fig. 2 is a plan thereof; Fig. 3 is an elevation of a half mold showing the piston cavity; Figs. 4 and 5 are sections on lines 4—4 and 5—5, respectively, of Fig. 1; and Fig. 6 is a detail showing the locking mechanism for holding the mold halves together.

My invention relates to metal molds, and particularly to molds used for casting pistons, consisting predominantly of aluminum. My invention comprises an arrangement of core pieces which permits ready assemblage of the mold and its core parts and greatly facilitates the separation of the mold from the piston. My invention also comprises the various features which I shall hereinafter describe and claim.

Referring to the drawings, 2 indicates the two complementary halves of a metal mold constructed to form a piston casting A of the desired shape, such as a skirted or cup-shaped piston, for internal combustion engines. Each half mold 2 has a semi-circular recess 3 which extends from the top of the half mold to its bottom, forming the passage through which the core pieces are inserted and withdrawn. The lower portions of the recesses 3 are offset at 3^a and form the top and outer side walls of the mold cavity. The mold halves 2 are mounted on a metal base member 4, the central portion 5 of which forms the bottom of the mold cavity. The handles 6 are secured to the halves 2, so as to permit the movement of these parts upon the base 4 into and out of casting position.

The mold core is preferably comprised of a plurality of metal members, which in the form here illustrated consist in a main core member 8, which forms in cross section at its opposite ends curved inner walls 9 of the mold cavity and has a downwardly extending lower portion 10, the bottom of which comprises the central portion of the inside face of the head of the piston cavity; in four thin sections 11 two of which are arranged

on each of the two opposite sides of the main section 8 (between the curved walls 9) and extend to the lower portion of the cavity, terminating in laterally extending projections 12, thus forming with the lower portion of the main section 8 the inner configuration of the cavity from the bottom of the cavity to the upper edge of the piston bosses; and in two sections 13, one of which is arranged outside each set of two of the sections 11 and completes with the portions 9 of the main section 8 the inner circumference of the cavity above the piston bosses. The lower end of each section 13 also forms the upper side of the web of the piston boss portions of the cavity and has a bearing upon the upper side of an inward projection 16, which has a circular opening therein for the formation of a wrist pin boss 26.

In assembling the molds preparatory to casting, the mold halves 2 are moved together over the base 4 and are locked to each other by the latches 14. The two core sections 13, which are supported by the levers 25, when elevated in the dotted line position shown at the right of Fig. 1, are next lowered into place by raising the levers 25, being held in position at the top by the flanges 15, which project outwardly over the top of the mold, and at the bottom by their engagement with the upper sides of the projections 16. The core sections 11 are then inserted inside the sections 13 and moved into position laterally with their lower ends 12 underlying the under sides of the inward projections 16. The core sections 11 are supported in such position by the lateral extensions 17, which rest on the upper ends of the sections 13, and then the main section 8 is inserted between the two sets of the sections 11 and lowered until its flanged upper end 18 rests on the top of the mold section, thus completing the installation of the core. The core members have draft to facilitate insertion and removal. The core pins 19 are then put in place and the mold may then be poured. I have shown a pouring gate 20, passage 21 and feeder 22, as illustrating one way in which the mold may be poured.

After the mold has been poured and a casting A formed therein, the core pins 19 are usually first removed, and the latches 14 released, so as to permit greater freedom of movement in taking out the core. The main core section 8 is next vertically re-

- 5 moved by its handle 23; the four sections 11 are then moved by their handles 24 laterally and inwardly to free their lower ends 12 from the piston bosses 26 and any ribs which 10 5 may form part of the casting which project from the sides toward the interior of the casting, and are then drawn upwardly; and, finally, the levers 25 which are attached to the core sections 13 are depressed and the 15 10 core sections 13 are thus elevated until their lower ends are clear of the skirt of the casting. The mold is then opened and the casting removed without the necessity of taking out the core pieces 13.
- 15 15 In case any of the core sections are frozen in, they may be freed by manipulation of the levers 25, as the flanged portions of the sections 13 underlie the extensions of the parts and hence, when the levers are depressed, the 20 20 parts 11 and 13 will thus be broken away from the casting.

I have found that molds constructed in accordance with my invention can be operated with great rapidity, since it is only 25 necessary to elevate and not to remove the core pieces 13. This results in a considerable saving of time both in assembling the molds and in removing castings therefrom, and in increasing the output of the molds. 30 The terms and expressions which I have employed are used as terms of description and not of limitation, and I have no intention, in the use of such terms and expressions, of excluding any mechanical equivalents of the features shown and described, or portions thereof, but recognize that various structural modifications are possible 35 within the scope of the invention claimed.

What I claim is:

- 40 1. In permanent molds for casting skirted pistons, a combination of a support, a pair of permanent mold members mounted on said support and movable bodily upon said support toward and away from each other, 45 said mold members being formed with com-

plementary curved walls comprising outer walls of a mold cavity for casting a skirted piston therein, a permanent sectional core comprising a plurality of sections supported from the top of the mold member and forming the interior side walls thereof, and levers attached to certain of such core sections co-operating with the top of the mold member to reciprocate the last mentioned core sections into and out of casting position. 50

2. In permanent molds for casting pistons, a combination of a support, a pair of permanent mold members mounted on said support and each having a recess complementary to the recess on the other member to 60 form the exterior of a mold cavity in which a piston is to be cast, a permanent core member movable relative to and spaced from said outer cavity walls to form inner walls of the mold cavity, said core being comprised of inner sections and outer sections, the outer sections being capable of being elevated and lowered into and out of casting position, and means cooperating with the top of the mold members for so raising and 65 lowering the said core sections.

3. In a permanent piston mold, a pair of mold members having complementary recesses on the inner faces thereof to form the outer side wall of a piston mold cavity, a 75 permanent core mounted between said complementary walls to form the inner wall of the cavity, said permanent core being comprised of a main section and outer sections forming a portion of the inner wall of the 80 mold cavity and a portion of the top edge thereof, said outer core sections having a bearing on the mold sections below the top of the cavity when in casting position, and means for elevating the said core sections 85 above the top of the casting after pouring to permit the removal of the casting without withdrawal of the core sections from the said recesses.

GUSTAV R. KELM.
